UNITED STATES PATENT OFFICE.

GEORGE G. FLOYD, OF RIVERSIDE, ILLINOIS.

STROPPING ELEMENT.

1,304,953.

specification of Letters Patent. Patented May 27, 1919.

Original application filed August 18, 1917, Serial No. 186,838. Divided and this application filed January 28, 1918. Serial No. 214,090.

To all whom it may concern:

Be it known that I, GEORGE G. FLOYD, a citizen of the United States, residing at Riverside, in the county of Cook and State of Illinois, have invented certain new and useful Improvements in Stropping Elements, of which the following is a specification.

In stropping or sharpening appliances, such, for example, as those employed for the sharpening of the edges of razor blades, difficulty has heretofore been experienced in securing the leather or other stropping facing to the rotary or oscillatory drum or roller in such manner that it will be adequately secured thereto, perfectly smooth, free from possibility of detachment, and in such a way that atmospheric changes shall have no effect on the securing means. It has heretofore been customary, for example, to glue or cement leather facings or surfacings on to the curved surfaces of wooden rollers or drums, but it is only with difficulty that the facing can be made to adhere perfectly smoothly and even if the leather is initially free from wrinkles, ridges, and the like, the moisture of the atmosphere is likely to act detrimentally on the cement, to say nothing of the possibility of the underlying wooden roller warping, twisting, or cracking. The present invention aims to overcome these various difficulties, by providing a stropping or sharpening element composed solely of metal and leather and other facing, the main body of the roller being formed of a properly bent metal shell to which the leather covering is fastened by the metal of the shell itself, as, for instance, by means of suitable holding teeth. In order to insure that the leather shall be perfectly smooth, it is applied or fastened to the metal sheet of which the roller or drum is composed before the latter is fully bent to shape, whereby, when the final bending of the metal occurs, the leather will be automatically stretched smooth over the drum's surface.

In the accompanying drawing forming a part of this specification, and to which reference should be had, I have illustrated a preferred and desirable embodiment of the invention and throughout the various views

of such drawing like reference characters refer to the same parts.

In this drawing:

Figure 1 is a face view or side elevation of one of the improved stropping or sharpening elements; 55 08

Fig. 2 is a plan view of the same;

Fig. 3 is a central longitudinal section on line 3—3 of Fig. 2;

Fig. 4 is a cross-section on line 4—4 of 60 08 Fig. 1;

Fig. 5 is an end view of the stropping element, and

Fig. 6 is a face view of the inner side of the gear mounted at one end of the drum. 65 08

Referring to the drawing, it will be observed that the new structure comprises a hollow shaft 10 made of sheet-metal bent up to cylindrical form, bringing its two longitudinal edges 11 and 12 into abutting relation. One end of such hollow or tubular shaft is provided with an integral end flange 13 and at its opposite ends the metal of the shaft is bent outwardly or shaped to form two integral short alined or registering keys 14 and 15. Over this shaft and bearing against the inner face of the flange a washer 16 is fitted, and next to this on the shaft and held against turning thereon by the key portion 14 is a gear 17, both the washer and 80 the gear having central openings to receive the shaft and its projection. As is more clearly shown in Figs. 3 and 6, the inner face of this gear has a groove 18 partially circular and partially flattened. Such 85 groove accommodates the end portion of a sheet-metal drum or roller 19 of the same shape, the opposite end of such member 19 being received and held in a similar groove 20 in the inner face of a disk 21 of the same 90 general shape as, but of somewhat larger size, than, the drum or roller. This disk is centrally perforated or apertured to fit the shaft and the key 15 which prevents it from turning thereon. At the outer side of such 95 disk the shaft is equipped with a flanged collar or sleeve 22 held thereon by upsetting the end of the shaft at a plurality of points 23. Thus, it will be seen that the sheet-metal body of the stropper is firmly held between 100

the gear and disk and caused to revolve therewith as the shaft rotates.

The meeting portions of the metal sheet forming the roller at the flat part thereof

- 5 are bent outwardly at 24, 24, and then in opposite directions at 25, 25, parallel to the body of the drum or roller at that place, the outer or marginal edges of such sections 25, 25, having inturned sharp teeth 26 embedded
- 10 in the leather facing 27 covering the metal body. Such parts 25, 25, and their teeth, constitute the sole securing means for the leather covering. Desirably, such leather piece is thus fastened to the sheet-metal
- 15 drum before the latter is fully bent to shape, whereby, when the completion of the bending is effected, the leather will be neatly and smoothly stretched over the outer surface.

Clearly, it is practically impossible for the 20 leather facing to become unfastened or detached in ordinary usage of the appliance, the body of the roller will not warp, twist, or crack, and there is no glue or cement likely to more or less lose its adhesive prop-

25 erties by reason of climatic conditions. With this improved device, the leather is always smoothly bent over the surface of the drum without danger of wrinkling, ridging, fluting, or detachment. The metal portion 30 of the drum is prevented from distortion by reason of the fact that its ends are securely held in the grooves of the end members, which, of course, obviates any difficulty from this score.

35 To those skilled in this art it will be apparent that many minor mechanical changes may be incorporated in the structure illustrated and described without departure from the invention and without sacrificing any of 40 its substantial advantages.

This application is a division of my former application, Serial No. 186,838, razor blade sharpeners, filed August 18, 1917.

I claim:

1. A stropping element of the character 45 described, comprising in combination a hollow roller formed of sheet-metal bent up transversely into general semi-cylindrical form, and a stropping facing transversely stretched over the outer surface of said 50 roller, the longitudinal edge portions of said metal roller at the flattened part thereof being bent outwardly in opposite directions over substantially the full length of the marginal portions of the facing, the outer 55 edges of said roller portions each having a series of inwardly-extended teeth embedded in the outer surface of said facing, said portions and teeth constituting the sole means fastening the facing to the roller, substan- 60 tially as described.

2. A stropping element of the character 65 described, comprising in combination a hollow roller formed of sheet-metal bent up transversely into general semi-cylindrical form, and a stropping facing transversely stretched over the outer surface of said 70 roller, the longitudinal edge portions of said metal roller at the flattened part thereof being bent outwardly in opposite directions over substantially the full length of the marginal portions of the facing, the outer 75 edges of said roller portions having inwardly-extended means embedded in the outer surface of said facing, said portions and inwardly-extended means constituting the sole means fastening the facing to the roller, substantially as described.

GEORGE G. FLOYD.
